UNITED STATES PATENT OFFICE.

WILLIAM COHLMAN, OF PHILADELPHIA, PENNSYLVANIA.

TROUSERS OR OVERALLS.

SPECIFICATION forming part of Letters Patent No. 352,297, dated November 9, 1886.

Application filed July 29, 1886. Serial No. 209,429. (No model.)

To all whom it may concern:

Be it known that I, WILLIAM COHLMAN, a citizen of the United States, residing in Philadelphia, Pennsylvania, have invented certain 5 Improvements in Trousers or Overalls, of which the following is a specification.

The main object of my invention is to dispense with the patch pockets with which overalls are usually provided, and this object I attain by forming a pocket by means of an extension of the leg-piece of the overalls, as fully described hereinafter.

In the accompanying drawings, Figure 1 is a rear view of a pair of overalls, showing my 15 improvement applied to hip-pockets. Fig. 2 is a section on the line 1 2, Fig. 1. Fig. 3 is a view of a modification. Fig. 4 is a side view of a pair of overalls, showing my improvement applied to the formation of a side pocket; and 20 Fig. 5 is a section on the line 3 4, Fig. 4.

A A' are the pieces forming the rear portions of the legs of the overalls, B being the breast-piece, and b b the shoulder-straps. It is usual in overalls to unite the two leg-pieces 25 A A' together by a seam, x, at the rear of the seat, the outside patch for the hip or side pocket being afterward sewed on; but this plan is objectionable, not only on account of the rear seam, but also because of the time 30 and labor required to properly form and sew on the patch pockets.

In carrying out my invention I provide each leg-piece A A' with an extension, a, Figs. 1 and 2, the extension of the piece A projecting 35 on the outside of the piece A', and the extension of the latter piece projecting on the inner side of the piece A, or vice versa. The two pieces are then stitched together on the line x, and a line of stitches, y, is run around each 40 of the extensions a, except at the top. This construction provides one pocket on the outside and another on the inside of the overalls; but in some cases the inner extension may be dispensed with and only one hip-pocket formed.

In Fig. 3 I have shown a pair of overalls in which a number of pockets or compartments are formed, the extension a in this case reaching to the side seam, w, and a series of lines of stitching, y, dividing the extension into a number of compartments. Overalls of this character are intended mainly for carpenters, paper-hangers, and artisans whose work requires that they shall have a number of tools within easy reach.

In Figs. 4 and 5 I have shown side pockets 55 formed by extensions a of the pieces A A' underlapping the front pieces, D D', of the leg. These pockets are stitched on the bottom and on one side and partly up the other side, leaving the top and part of one side open, the extension a being entirely covered and only the stitching exposed.

It will be evident that trousers can be provided with pockets in the manner described without departing from my invention. 65

I claim as my invention—

1. Overalls or trousers having a pocket consisting of a portion projecting from one of the leg-pieces and overlapping and permanently secured to the adjacent leg-piece, all substantially as specified. 70

2. Overalls or trousers, each of the rear leg-pieces of which has a projecting pocket portion overlapping and permanently secured to the adjoining leg-piece, one of said overlapping pocket portions being on the outside and the other on the inside, all substantially as specified. 75

In testimony whereof I have signed my name to this specification in the presence of two 80 subscribing witnesses.

WILLIAM COHLMAN..
